UNITED STATES PATENT OFFICE.

CHARLES A. HUNT, OF OAKLAND, CALIFORNIA.

RAILROAD JOINT.

Application filed August 27, 1928. Serial No. 302,245.

The present invention relates to improvements in railroad joints, and its principal object is to provide a joint for two abutting rails in which each rail is extended to run parallel to the abutting rail, so that a wheel passing over the joint is carried by the extension of one rail while making contact with the other rail, whereby its weight is transferred from one rail to the other smoothly and without interruption of support.

It is particularly proposed by this means to eliminate low joints and the flattening of the rail ends since a continuous surface is provided and any chance for dropping of the rail ends is removed.

It is further proposed to arrange these extensions and to shape the rail ends in such a manner that each extension is accommodated in a complementary recess in the abutting rail, so that the joint is kept within the confines of the rails.

It is further proposed to join the two rail ends in such a manner as to allow for expansion and contraction of the rails under the influence of changes in temperature.

It is further proposed to arrange this joint in such a manner that it may be used in connection with old rails by providing joint sections adapted to be welded to the end faces of existing rails.

Further objects and advantages of my invention will appear as the specification proceeds.

The preferred form of my invention is illustrated in the accompanying drawing in which

Figure 1 shows a side elevation of my rail joint;

Figure 2, a top plan view of the same;

Figure 3, a cross section taken along line 3—3 of Figure 1;

Figure 4, a longitudinal section taken along line 4—4 of Figure 1;

Figure 5, an end view of a joint section;

Figure 6, a side view thereof;

Figure 7, an end view taken from the opposite end;

Figure 8, a top plan view of a joint section.

While I have shown only the preferred form of the invention, I wish to have it understood that various changes or modifications may be made within the scope of the claims hereto attached without departing from the spirit of the invention.

In its preferred form, my invention com-

prises two complementary joint sections, one of which is illustrated in Figures 5 to 8 while the two are shown in place in the Figures 1 to 4. The rails 1 to be joined are of the ordinary I-beam type including a base 2, a web 3 and a top flange 4 providing the surface on which the wheel of a vehicle rides. The joint sections 6 and 7, the former of which is shown in detail in Figures 5 to 8, may be welded to the ends of the two rails to be joined as shown at 8. Each of the joint sections comprises a base 9 co-extensive in width and corresponding in shape to the base of the rails. From this base rises, at the end where the joint section is to be joined to the rail, a short web 11 co-extensive in height with the height of the rail and in width, with the width of the supporting face of the rail. From this short web 11 extends an offset web 12 of half the width of the short web 11 and of the same height, and this offset web extends to the end of the base 9 and beyond the same to such an extent that the extension beyond the base is equal in length to the offset web rising from the base.

It will be seen that this construction allows the two offset webs of the two joint sections to be placed alongside of one another in the manner shown in Figures 2 and 4, within the confines of the surface of the rails, and to be fastened together by means of bolts, or rivets 13 passing through registering perforations in the two offset webs. It will be noted that some of the perforations, as shown at 14, are made elongated so as to allow of contraction and expansion of the rails under the influence of changes in temperature.

Since the extension of the offset web beyond the base is equal to that portion of the web above the base, it is apparent that the abutting bases will approximately contact when the rails are joined, except, of course, for the allowance made for expansion and contraction.

The manner of joining two rails by my improved means is apparent from the foregoing description. The two joint sections 6 and 7 are first welded to the ends of two rails, whereupon the rails are placed on suitable foundations with the offset webs arranged alongside of one another. The application of the bolts or rivets 13 completes the operation.

The advantages of my construction should be readily understood. A wheel coming from one direction is supported by the offset extension of the first rail, while it makes contact

with the extension of the other rail and gradually distributes its weight over both of the extensions until it reaches the body portion of the second rail, when its weight is taken over by the latter. At no time is there any lack of supporting face and no interruption in the support of the wheel, so that there is no chance for the dropping of the wheel, which is the cause for low joints and the flattening of the abutting ends of the rails.

I claim:

A portable railroad joint comprising two

short rail sections, each comprising a base, a short web rising therefrom at one end coextensive in height with the height of the rails to be joined and in width with the width of the bearing surface of the rails and adapted to be welded to said rails, an offset web of half the width and the same height connecting with the short web and extending beyond the base for side by side engagement with the offset web of the other section and means for fastening the two offset webs together.

CHARLES A. HUNT.
